CUP PASTRY DISPENSER

James Balton, Baltimore, Md., assignor to
Maryland Baking Company, a corporation of
Maryland

Application March 21, 1940, Serial No. 325,242

7 Claims. (Cl. 312—43)

My present invention relates to dispensers for ice cream cones and other cup pastry, and it particularly seeks to provide an improved dispenser, one which will occupy a minimum of counter space, one which can be easily and cheaply manufactured, and one in which the cones can be kept crisp, their flavor maintained at all times, and in which they can be kept free from dust and contamination.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a side elevation of the dispenser.

Fig. 2 is an inside view of the removable cylinder unit.

Fig. 3 is an enlarged detail section on the line 3—3 of Fig. 2.

Fig. 4 is a detail elevation of a portion of the apparatus later again referred to.

Fig. 5 is a section on the line 5—5 of Fig. 9.

Fig. 6 is a top plan view of the parts shown in Fig. 9.

Fig. 7 is an enlarged detail elevation and part vertical section of a cone guide's lower end.

Fig. 8 is a detail view on a smaller scale of the upper ends of two cone guides, showing how they are united.

Fig. 9 is a section on a larger scale, on the line 9—9 of Fig. 6.

Fig. 10 is a plan view of the apparatus, the removable cylinder unit of the magazine case being omitted.

Fig. 11 is a detail view of a lower connection used between two cone guides or cages and which cooperates with the holding clips 20.

In the drawings, in which like numbers of reference indicate like parts in all the figures, 1 is a suitable base on which is a post or standard 2 carrying a bracket 3 that is welded or otherwise attached to the under side of the table 4. The table has a skirt 5 and a central raised disc-like portion 6 apertured for the tubular screw 7 which is secured in place by nuts 8, the screw passing through washers 9 and the apertured end of the spring arm 23, later again referred to.

A lamp socket 35 is secured to the upper end of the screw 7. The skirt 5 has an elongated L-slot 10 through which the magazine turning handle and latch member 22, carried by spring arm 23, projects.

The table 4 has a single discharge hole or opening 11 surrounded by a ring 12 spot welded or otherwise secured to the under side of the

table 4 and provided with three pairs of triangularly disposed hook-lugs 13 around which a resilient band 14 is passed to serve as a cone stack support. A gate 15, pivoted and operated by manipulating a knob 16, is mounted beneath the table 4 to close the opening 11. (In this application I make no claim to the parts 12 to 16 inclusive as they constitute a part of the subject matter of my application Ser. No. 225,447, filed

August 17, 1938.)

The cone magazine includes a bottom and a removable transparent (preferably) cylinder to which is fixed a top, the cylinder and top comprising a unit separate from the bottom of the magazine.

The bottom of the magazine consists of a rotatable plate 18 and a rim 17 rigidly connected to the plate 18. The plate 18 may have radial strengthening ribs 19 and it is provided with cone guide-cage clips 20, and a series of cone-passing holes 21 symmetrically arranged about the axis of the magazine. The rim 17 has spaced notches 24, one for each hole 21. These notches cooperate with the magazine turning handle-latch 22 and L-slot 10, as will later more fully appear.

The plate 18 is centrally apertured to fit over the central disc-like guide 6 and is held down on the table 4 by gravity and by a ring 25 removably secured to the table and overlapping the joint between 18 and 6, as clearly shown in Figs. 9 and 10.

Removably mounted as a single unit on the bottom plate 18 of the magazine, is a cone guide cage. This cage is composed of a number of distinct units 26, one for each hole 21. Each unit 26 comprises a cage for a single stack of cones and consists of a lower tubular collar or base 27 formed by a sheet of metal bent back upon itself at 28, and over the lower portions of a set of wire rods 29. The rods 29 have notches 30 into which portions 31 of the collar part 28 are pressed to lock the rods to the collar rigidly.

At the top the rods 29 are capped by a metal ring 32 bent back upon itself and secured by portions 31 pressed into notches 30 in the upper ends of the rods 29 (see Fig. 8).

Each cone stack guide unit 26 is rigidly secured to those adjacent by means of upper and lower bridge pieces 33 and 34, respectively, so that all units 26 are united into a single cage which is placeable and removable as a unit. The lower bridge members or connectors 34 (see Fig. 11) are H-shape to fit the clips 20, and thus center the units 26 over the respective holes 21 with which they cooperate.

The magazine includes a cylinder 36 (preferably transparent) which fits into the annular wall or ring 17 and rests on the plate 18. The upper end of this cylinder 36 is secured to a top

37 to which a knob 38 is secured by a nut and bolt 39. The bolt 39 also serves to secure to the under side of the top 37 a foraminous cup 40 in which is a foraminous basket 41 containing a moisture absorber 42 of suitable material, and beside the basket is a cake 43 of flavoring material which gradually gives off a suitable substance, such as vanilla for instance, which permeates the atmosphere within the magazine and keeps the cones from losing their natural flavor and odor.

The cylinder 36, when made of Cellophane or the like, preferably has its lower end reinforced by a metal band or ring 44.

Current is conveyed from an external source, through an on-off switch 46 on the base 1 via wires 45, to the lamp socket 35 in which a light bulb (not shown) is placed to illuminate the inside of the magazine.

It will be seen by reference to Figs. 1 and 4 that the slot 10 has a notch at one end only and is of a length to extend from one notch 24 to the next adjacent one. The notches 24 extend above the straight-way part of the slot 10. When it is desired to turn the magazine, handle-latch 22 is moved down and then to the left end (Fig. 1) of slot 10 where it springs up into notch 24 at the left. By moving handle-latch 22 from left to right the magazine 17-36-37 and contents are carried one step to the right to bring another stack of cones into dispensing position over hole 11.

With the cages 26 filled with cones, the attendant opens the gate 15, whereupon the cones in the cage immediately above opening 11 drop until the stack rests on the band 14. They may then be removed, one at a time, by the attendant in the usual way. When the cage that is over hole 11 is empty, the next one is brought into register by turning the magazine as heretofore described.

From the foregoing description, taken in connection with the accompanying drawings, it is thought that the complete construction operation and advantages of the invention will be clear to those skilled in the art to which it relates.

What I claim is:

1. In a cup-pastry dispenser, a table having a dispensing hole, a magazine rotatably mounted on the table to turn on a vertical axis and including a base part having a series of discharge holes, a cylinder and cylinder top removably mounted on the base part, a cone guide comprising a series of cone-stack cage units, means uniting said cage units together into a unitary structure, and means for retaining said guide removably in place on the magazine's bottom part with the respective cage units in register with the respective holes in said base part.

2. In a cup-pastry dispenser, a table having a dispensing hole, a magazine rotatably mounted on the table to turn on a vertical axis and including a base part having a series of discharge holes, a cylinder and cylinder top removably mounted on the base part, a cone guide comprising a series of cone-stack cage units, means uniting said cage units together into a unitary structure, and means for retaining said guide removably in place on the magazine's bottom part with the respective cage units in register with the respective holes in said base part, said retaining means comprising clips cooperatively engaging with certain of said uniting means.

3. In a cup-pastry dispenser, a cone guide comprising a plurality of individual cone-stack guiding cages each complete in itself through which the cones are fed, and bridge members 5 uniting said cages in an annular series thereby constituting a single unit cage, a rotatable plate having a discharge hole for each cage, means for retaining said unit cage on said plate, and a table on which said plate is rotatably mounted 10 and which has a single discharge hole with which any desired one of the plate discharge holes may be brought into register as desired.

4. In a cup-pastry dispenser, a cone guide comprising a plurality of individual cone-stack 15 guiding cages through which the cones are fed, and bridge members uniting said cages in an annular series thereby constituting a single unit cage, each of said cages comprising top and bottom sheet metal rings and spaced wire rods, said 20 rings being fitted over the ends of said rods and secured thereto by means of pressed-in portions of the rings projected into grooves in the rods.

5. In dispensers of the character described, a 25 table having a top and a dispensing hole, a plate on said top, means to pivot said plate on a central axis to turn on said table, said plate having a plurality of apertures constructed to register one at a time with said dispensing hole, a cup guide comprising a set of individual cup-guiding cages, 30 one for each plate aperture, bridge pieces connecting the individual cages together into a unitary structure, and means removably holding said cup guide in place on said plate.

6. In dispensers of the character described, a 35 table having a top and a dispensing hole, a plate on said top, means to pivot said plate on a central axis to turn on said table, said plate having a plurality of apertures constructed to register one at a time with said dispensing hole, a cup 40 guide comprising a set of individual cup-guiding cages, one for each plate aperture, bridge pieces connecting the individual cages together into a unitary structure, means removably holding said cup guide in place on said plate, and means carried 45 by said table and operatively connected with said plate for turning said plate one step at a time a distance necessary to move one cage out of register with an adjacent cage and into register with said table's dispensing hole.

7. In dispensers of the character described, a 50 table having a top with an annular skirt at its margin and a dispensing hole, a plate on said top, means to pivot said plate on a central axis to turn on said table, said plate having a plurality 55 of apertures constructed to register one at a time with said dispensing hole, a cup guide comprising a set of individual cup-guiding cages, one for each plate aperture, bridge pieces connecting the individual cages together into a unitary structure, means removably holding said cup guide 60 in place on said plate, and means carried by said table and operatively connected with said plate for turning said plate one step at a time a distance necessary to move one cage out of register with an adjacent cage and into register with said table's dispensing hole, said last named 65 means comprising a handle-latch, an L-shaped slot in said table's skirt, and a rim on said plate overlying said skirt and having spaced handle-latch receiving notches.

JAMES BALTON.
